UNITED STATES PATENT OFFICE.

JOHN C. STILLMAN, OF APPLETON, WISCONSIN.

CLOTHES-LINE PROP.

Specification of Letters Patent. Patented Nov. 13, 1917.

1,246,676.

Application filed January 12, 1917. Serial No. 142,055.

To all whom it may concern:

Be it known that I, JOHN C. STILLMAN, a citizen of the United States, residing at Appleton, in the county of Outagamie and State of Wisconsin, have invented new and useful Improvements in Clothes-Line Props, of which the following is a specification.

This invention relates to improvements in clothes line props and has particular application to an extensible prop.

The object of this invention resides in the provision of a device of this character which is simple, durable, and efficient in its construction and which is provided with a simple locking means for locking the sections of the prop in adjusted positions so as to prevent relative movement of the sections when the prop is supporting a line.

The invention further consists in the novel features of construction and arrangement of parts as will be hereinafter described, and in which:

Figure 1 is a side elevation of the device constructed in accordance with my invention.

Fig. 2 is an edge elevation.

Fig. 3 is a transverse section taken on the line 3—3 of Fig. 1.

Fig. 4 is a transverse section taken on the line 4—4 of Fig. 1.

Referring to the drawings in detail, my invention comprises two poles or sections 1 and 2 respectively, which are formed of any suitable material such as wood or the like, and which are preferably of rectangular formation in cross section. The sections 1 and 2 are adapted to be arranged in contiguous and overlapped relation, the section 2 being formed with a guide bracket 3, the latter being formed of a single strip of metal

40 which is bent in the form of a rectangle and is secured to the section 2 by means of a transversely extending bolt 4. The bracket 3 is so arranged upon the section 2 as to 45 have the opposite ends thereof projecting beyond the opposite sides of the section to provide a rectangular opening through which the section 1 is adapted to extend.

The bracket 3 is preferably arranged adjacent the lower end of the section 2 and is of such a size as to loosely receive the section 1 to permit the sliding movement of the sections in relation to each other.

The section 1 is provided adjacent its upper end with a pair of strips 5 which are secured to the opposite side faces of the sec-

tions at the ends by means of the bolts 6, the strips extending laterally of the section and having their free ends connected by means of a bolt 7. The section 2 is adapted 60 to extend between the strips 5 while, connecting the strips upon the outer side of the section 2, is a transversely extending bolt 8 which is threaded throughout its entire length. This bolt has slight movement with 65 relation to the strips 5. Mounted upon the bolt 7 and disposed between the strips 5 is an eccentric roller 9, the latter being formed of any suitable material such as wood or the like, and being of such a diameter as to 70 cause the cam surface thereof to engage the bolt 8 when in active position. It will be seen from the foregoing that after the roller 9 is forced into engagement with the bolt 8 the said parts are held against relative movement by tightening the nut on the bolt 7, whereby the roller 9 is clamped between the strips 5. Thus a lock is provided for holding the sections 1 and 2 at adjusted positions 75 with relation to each other. In applying 80 the strips to section 1 by bolt 6 there must be space enough left between section 2 and threaded bolt 8 to let section 2 loosely play when strips 5 are swung at right angles to sections 1 and 2. To lock press down on 85 the free end of strips 5, thereby pressing bolt 8 firmly against section 2, thereby securely locking the parts. It is obvious that by swinging strips 5 to right angles again it will disengage the bolt 8, thereby permitting 90 section 2 to return to its normal or disengaged position, whereby the sections may be free to move.

To retain the prop in active position upon a clothes line, I provide the upper end of 95 the sections 2 with a clip 10, which is formed of a single length of resilient wire. The clip 10 is bent between its ends to provide the spaced fingers 11 and 12, the finger 12 being relatively longer than the finger 11 100 as is clearly illustrated in the drawings. The confronting strands of the finger are bent to provide the restricted entrance passage 13, the lower end of the space between the fingers being relatively wider as shown. It 105 will be evident from the foregoing construction that when the prop is applied to a clothes line, the line will be passed between the fingers 11 and 12, the inherent resiliency of the fingers permitting the fingers to expand to allow the insertion of the line as 110 will be understood. The line having been

- inserted within the lower portion of the space between the fingers, the prop may be free to move upon the line as will be understood. The opposite ends of the clip are secured to the sections by means of the plate 14, the plate being secured to the section by means of the bolt 15, while the ends of the clip are interposed between the clip and the adjacent faces of the sections.
- 10 To prevent the excessive wearing of the section 1 when in supported position, I form its lower end with a reduced annular portion 16 upon which is mounted a ferrule 17, the latter being preferably formed of metal.
- 15 It is thought from the foregoing that the construction and operation of this device

will be apparent to those skilled in the art without further description, and therefore a more extended explanation has been omitted.

Having described my invention what is claimed is:—

A clothes line prop comprising two sections, guide brackets formed on the sections and slidably receiving the sections, a bolt 2 carried by one of the brackets and an eccentrically mounted wheel engageable with the bolt to force the same into engagement with one of the sections to lock the sections against movement.

In testimony whereof I affix my signature.

JOHN C. STILLMAN.
